I. LESTER.
HAY RACK HOIST.
APPLICATION FILED JAN. 23, 1908.

903,874.

Patented Nov. 17, 1908.

UNITED STATES PATENT OFFICE.

IRWIN LESTER, OF TUSCOLA, ILLINOIS.

HAY-RACK HOIST.

No. 903,874.

Specification of Letters Patent. Patented Nov. 17, 1908.

Application filed January 23, 1908. Serial No. 412,325.

To all whom it may concern:

Be it known that I, IRWIN LESTER, citizen of the United States, residing at Tuscola, in the county of Douglas and State of Illinois, have invented certain new and useful Improvements in Hay-Rack Hoists, of which the following is a specification.

The object of this invention is an improved device which is designed to remove a hay-rack or the like from its running-gear, and which is adapted to support the hay-rack in a convenient position out of the way until again desired for use and to then remount the hay-rack upon the running-gear.

With this and other objects in view that will more fully appear as the description proceeds, the invention consists in certain constructions and arrangements of parts that I shall hereinafter fully describe and claim.

For a full understanding of the invention and the merits thereof, reference is to be had to the following description and the accompanying drawing, in which:

Figure 1 is a perspective view of my improved hay-rack hoist. Fig. 2 is a transverse section thereof showing it applied, and Fig. 3 is a detail view of a modified form of bracket.

Corresponding and like parts are referred to in the following description and indicated in all the views of the drawing by the same reference characters.

Referring to the drawing, the numeral 1 designates a suitable supporting frame for this improved device, such as a crib wall, said frame comprising standards 2 and a breast work 3 secured to the lower ends thereof.

Two brackets 4 are attached to the breast-work and comprise preferably square wall-posts 5, braces 6 and horizontally-disposed arms 7, said latter being provided intermediate of their ends with outwardly facing shoulders 7^a. The wall posts 5 are mounted in vertically alining upper and lower bearing straps 8 that are secured to the breast-work, and are formed with square sockets 9 in which the wall posts fit, the lower ends of said wall-posts resting on sustaining blocks 10 fastened to the breastwork.

In order that the brackets 4 may be quickly turned out of the way and against the breast-work when the device is not desired for use, the wall-posts 5 are formed below each bear-

ing-strap with an annular reduced portion 55 11, whereby said brackets may be raised so that the reduced portions are received in the sockets 9, and may be quickly swung around at right angles to their original positions and then lowered in the bearing straps and thus 60 obviously locked in such positions.

A latch 12 is pivotally secured intermediate of its ends to the upper end of one of the standards 2, with the outer end of the latch projecting from the standard and formed at 65 its lower edge with an inwardly-facing shoulder 13, a pin 14 being secured in said outer end of the latch and extending laterally therefrom, as shown. A stud 15 is preferably secured in the standard in order to 70 limit the downward movement of the latch.

A hoisting member 16 is connected to the standard 2 and in the present instance is in the form of a triple block and tackle, the standing block 17 of which is secured to the 75 outer face of the standard above the projecting outer arm of the latch.

In the practical use of my improved device, a hay-wagon from which it is desired to remove the hay-rack, is drawn up contiguous to the frame 1 and one side sill of the rack is placed upon the arms of the brackets 4 against the shoulders 7^a thereof, while the running block of the block and tackle is secured to the opposite sill of the rack. The 85 running end of the fall is passed beneath the pin 14 of the latch and is then pulled, which slightly raises the latch and swings the rack upwardly into a substantially vertical position contiguous to the frame, said running 90 end being then slackened which permits the latch to fall into engagement with the upper side of the rack and hold it securely in position.

When it is desired to remount the rack 95 upon the running-gear, the running end of the fall is pulled taut to raise the latch out of engagement with the rack, and the latter is conveniently lowered into its original position.

It is to be understood that any suitable means may be employed to permit the brackets to be turned out of the way when not in use, for instance, the arms 7^b may be hingedly connected to the wall-posts 5^a so as to swing 100 in vertical planes and the braces 6^a similarly secured at their upper ends to the arms, the lower ends of said braces being removably

secured to the wall-posts as clearly illustrated in Fig. 3, and thus adapting the brackets to be folded when desired.

Having thus described the invention, what I claim is:

5. 1. A device of the character described, comprising a supporting frame adapted to have one side of a hay rack rest thereon, means for swinging the hay rack upwardly about said side, and means carried by the frame for engaging the other side of the hay rack to hold the latter in raised position.
10. 2. A device of the character described, comprising a supporting frame, brackets secured to the frame and adapted to have one sill of a hay-rack rest thereon, a hoisting member connected to said frame and designed to be secured to the other sill of the hay-rack and to raise the latter, and a latch secured to the frame and arranged to engage the hay-rack whereby to hold the latter in raised position, as and for the purpose set forth.
15. 3. A device of the character described, comprising a supporting frame, brackets secured to the frame, a latch pivotally secured to the frame and projecting therefrom, said latch having a pin secured in its projecting end, and a hoisting member connected to the frame and passing beneath the pin of the latch, as and for the purpose set forth.
20. 4. A device of the character described, comprising a supporting frame, brackets attached to the frame and embodying square wall-posts and arms, vertically-aligning upper and lower bearing straps secured to the frame and formed with square sockets in which the
25. wall-posts fit, sustaining blocks secured to the frame and upon which the lower ends of the wall-posts rest, and a hoisting member connected to the frame, said wall-posts being formed below the respective bearing straps with reduced portions, as and for the purpose set forth.
30. 5. A device of the character described, comprising a supporting frame, brackets secured to the frame and adapted to have one side of a hay rack rest thereon, means for raising the hay rack, and a latch secured to the frame and arranged to engage the hay rack to hold the latter in raised position.
35. 6. A device of the character described, comprising a supporting frame, brackets secured to the frame and adapted to have one side of a hay rack rest thereon, means for raising the hay rack, and a latch secured to the frame and arranged to engage the hay rack to hold the latter in raised position, the rack-raising means being arranged to operate the latch.
40. 7. A device of the character described, comprising a supporting frame, brackets secured to the frame and angularly disposed thereto, said brackets being adapted to have one side of a hay rack rest thereon, means for raising the hay rack, and means for holding the brackets in an inoperative position.

In testimony whereof I affix my signature in presence of two witnesses.

IRWIN LESTER. [L.S.]
